UNITED STATES PATENT OFFICE

137,283

DESIGN FOR A GOLF CLUB

John Jay Jakosky, Lawrence, Kans.

Application August 6, 1942, Serial No. 107,833

Term of patent 14 years

To all whom it may concern:

Be it known that I, John Jay Jakosky, a citizen of the United States, residing at Lawrence, in the county of Douglas and State of Kansas, have invented a new, original, and ornamental Design for a Golf Club, of which the following is a specification, reference being had to the accompanying drawing, forming a part thereof.

Fig. 1 is an elevational view of the golf club showing my new design, with one of the striking faces thereof in plan.

Fig. 2 is an enlarged elevational view of the golf club with a second striking face in plan and with a portion of the shaft separated from the head of the club.

Fig. 3 is an enlarged elevational view of the

golf club with a third striking face in plan and with a portion of the shaft separated from the head of the club.

Fig. 4 is an enlarged elevational view of the golf club with a fourth striking face in plan and with a portion of the shaft separated from the head of the club.

Fig. 5 is a top plan view of the golf club as illustrated in Fig. 1 with a portion of the shaft broken away, and

Fig. 6 is a bottom plan view of the golf club head.

I claim:

The ornamental design for a golf club, as shown.

JOHN JAY JAKOSKY.
